UNITED STATES PATENT OFFICE.

ANDREW L. WAGSTAFF, OF KANSAS CITY, MISSOURI, ASSIGNOR TO WAGSTAFF BOX MANUFACTURING COMPANY, OF KANSAS CITY, MISSOURI, A CORPORATION OF MISSOURI.

BOTTLE CASE.

Application filed April 11, 1924. Serial No. 705,824.

To all whom it may concern:

Be it known that I, ANDREW L. WAGSTAFF, a citizen of the United States, residing at Kansas City, in the county of Jackson and State of Missouri, have invented certain new and useful Improvements in Bottle Cases; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to bottle cases and the primary object thereof is to provide a bottle case having a removable bottle receiving frame so that in the event that the case becomes broken or otherwise deteriorated, the frame can be reclaimed to serve as part of the structure of a new case so that the cost of renewals will be reduced to a minimum.

The invention is especially designed, though not necessarily confined to milk bottle cases. Such cases are usually constructed of wood and not infrequently they utilize metal compartmental frames to receive the bottles. Ordinarily the frames are so associated with the cases that when the wooden portion of the case becomes broken the entire case is thrown away.

My invention is so constructed that the bottle carrying frame of the case is removable fastened to the case, the bottle carrying frame being a unitary structure which can be bodily removed from the wooden portion of the case which has become worn or broken, and associated with a new wooden structure to make a substantially new case, the frame being rugged enough to last indefinitely. In order to clearly distinguish between the destructible portion of the case and the indestructible portion of the case, I will term the wooden portion the outer frame and the compartmental frame the inner frame, the details of the various parts being specifically referred to by numerals of reference in the

following description, reference being had to the accompanying drawings, in which 50

Fig. 1 is a perspective view of a complete bottle carrying case constructed in accordance with my invention.

Fig. 2 is a sectional view through part of one of the end walls showing the means of 55 securing the bottom rods.

Fig. 3 is a sectional view through one of the walls of the case showing the manner of securing the top member of the inner frame to the outer frame.

Fig. 4 is an inverted perspective view of the inner frame, and

Fig. 5 is an inverted perspective view of the outer frame.

The outer frame is shown as rectangular, 65 being provided with side walls 1 and 2 and end walls 3 and 4, fastened together by corner braces 5 of appropriate construction. The walls 1, 2, 3 and 4 will preferably be constructed of wood to receive the inner 70 frame illustrated in Fig. 4. The inner frame consists of an upper deck 6 and a lower deck 7. The upper deck has longitudinal flat bars 8 and transverse flat bars 9 intersecting one another, the ends of the bars being provided with perforate right angular portions 10 and 11 for the bars 8 and 9 so that the ends of the bars 8 and 9 may be fastened to the walls of the outer case by screws 12 passing through the perforations 80 in the extensions 8 and 9 and through the internally threaded sleeve nuts 13 (see Fig. 3). The bars 8 and 9 are connected at their points of intersection by substantially rectangular angle plates 14 having edge flanges 85 which are drawn down in the form of ears 15 to receive the upper edges of the bars 8 and 9 and which are secured thereto by rivets or spot welding so that the angle plates 14 rigidly brace and tie together the bars 8 and 9 at their points of intersection. The edges 16 of the tie plates are curved on arcs to conform to the peripheries of the bottles which they are to receive.

The bottom of the inner frame consists of 95 transverse bars 17 having right angularly

bent ends 18 conforming to the ends 10 and 11 of the bars 8 and 9, the ends 18 being secured to the walls of the outer frame in substantially the same manner as the bars 8 and 9, 6 that is preferably by fastening means shown in detail in Fig. 3.

- The transverse bars 17 carry longitudinal bottom rods 19, each having right angular extensions 20 and 21 at its respective ends, 10 the extensions being threaded at 22 to receive securing nuts 23. The lower ends of the end walls are provided with cut-in recesses 24 having through openings 25 therein to receive the ends 20 or 21 as the case 15 may be, the cut-in recesses 24 being provided for the purposes of fastening the rods 19 to the outer frame of the case above the bottom thereof. The end walls may consist of two members for example 26 and 27, the member 20 27 in the form of a bar spaced from the member 26 so that access to the nuts 23 may be had through the spaces 28.

The bottom member or deck of the inner frame is connected to the top deck of the inner frame by vertical bars 29 so that the upper deck is spaced from the lower deck or bottom of the case. In constructing the case, the outer frame is made in accordance with the illustrated embodiment shown in 25 Fig. 5 and the inner frame is fabricated in accordance with the construction shown in Fig. 4, the outer frame being inverted and the inner frame inverted. The inner frame is slipped into the outer frame so that the ends 20 and 21 of the rods 19 are received in the recesses 24 with the ends 20 and 21 projecting through the through openings 25 so that nuts 23 can be screwed on the threaded portions 22 to draw the rods 19 30 tight against the ends of the recesses 24. The ends of the bars 8, 9 and 17 are then secured to the walls of the outer frame in a manner substantially like that illustrated in Fig. 3 so that the inner frame is rigidly 35 fastened to the outer frame, the inner frame bracing the outer frame and the outer frame serving as a co-operating protecting means for the inner frame so that the case will be rigid and practically indestructible from 40 ordinary usage.

It sometimes happens that the wood deteriorates or from abuse or excessive use becomes broken. In that event, it will be only necessary to take off the nuts 23, 45 remove the screws 12, take out the thimbles or slip nuts 13 and reassociate the inner frame with the new outer frame whereupon a new complete case will be provided.

Inasmuch as the main cost of production 50 is in the inner frame, it will be apparent that a new case can be constructed from a new outer frame and an old used inner frame at a relatively small cost.

What I claim and desire to secure by 55 Letters-Patent is:

1. A bottle case comprising an outer frame and an inner frame, the outer frame having end walls and side walls, the inner frame comprising an upper deck and a lower deck connected together in spaced relation, the 70 upper deck having longitudinal bars and transverse bars and substantially rectangular tie-plates provided with grooves to receive the longitudinal bars and transverse bars, means for rigidly fastening the 75 grooved portions of the tie plates to the respective bars and means for removably securing the inner frame to the outer frame.

2. A removable inner frame for bottle cases consisting of an upper deck having 80 longitudinal bars and transverse bars, tie plates connecting the longitudinal bars and transverse bars at their points of intersection, the tie plates being curved to conform to the contour of the bottles to be received 85 between the longitudinal bars and transverse bars, the lower deck having flat bars connected to the upper deck in spaced relation and rods extending through the bars of the lower deck and provided with means for 90 removably securing the rods to the complementary member of the bottle case.

3. A removable metallic inner frame for bottle cases comprising an upper deck consisting of intersecting longitudinal bars and 95 transverse bars, substantially rectangular, tie plates at the points of intersection of the transverse bars and the longitudinal bars, the tie plates having depending flanges embracing the upper edges of the longitudinal 100 bars and the transverse bars, means for rigidly fastening the flanges to the respective bars, a lower deck for supporting the bottom of the bottles and means for fastening the lower deck to the upper deck in 105 spaced relation.

4. A removable bottle receiving frame for bottle cases comprising an upper deck and a lower deck, spacing bars connecting the upper deck to the lower deck, the upper 110 deck consisting of longitudinal bars and transverse bars, tie plates fastening the longitudinal bars to the transverse bars, said tie plates having flanged edges embracing the upper edges of the longitudinal bars and 115 transverse bars and rigidly connected thereto, the lower deck comprising perforate bars and rods extending through them, the rods having threaded ends to receive removable fastening devices to secure them to the walls 120 of the bottle case, the rods being arranged in parallel beneath the openings formed by the longitudinal bars and the transverse bars of the upper deck so that the rods constitute supports for the bottom of the bottles.

5. A bottle case comprising an outer frame and an inner frame, the outer frame having side walls and end walls, the inner frame 125 consisting of metallic longitudinal bars and transverse bars, the respective bars having 130

their ends bent at right angles, means for removably fastening the ends to the walls of the outer frame, tie plates having flanged corners embracing the longitudinal bars and 5 end bars rigidly secured thereto, the lower deck of the inner frame having perforate bars, with rods extending through the bars

and provided with threaded ends to receive fastening devices for removably securing the threaded ends to the outer frame and 10 spacing bars connecting the lower deck to the upper deck.

In testimony whereof I affix my signature.
ANDREW L. WAGSTAFF.
